UNITED STATES PATENT OFFICE.

HENRY F. WILL, OF MICHIGAN CITY, INDIANA.

GAS-ENGINE.

1,089,173.

Specification of Letters Patent.

Patented Mar. 3, 1914.

Application filed November 4, 1911. Serial No. 658,493.

To all whom it may concern:

Be it known that I, HENRY F. WILL, a citizen of the United States of America, residing at Michigan City, in the county of LaPorte and State of Indiana, have invented certain new and useful Improvements in Gas-Engines, of which the following is a specification, reference being had therein to the accompanying drawings.

This invention relates to gas engines and more especially to the two-cycle variety thereof, and it has for one of its objects the provision of an improved engine of this character in which a differential piston is employed, one section of which constitutes the power piston operated by the explosion in the cylinder while the other constitutes the compressing and charging device whereby fresh gas is supplied to the explosion cylinder.

One feature of the invention is the control of the intake of the gas from the carbureter by the movement of the piston which latter acts as a valve for automatically shutting off and admitting the gas at the proper point of the piston stroke.

Further objects of the invention will hereinafter appear and be particularly defined in the claim.

The invention has been clearly illustrated in the accompanying drawing which represents a vertical section of an engine embodying my invention.

Referring to the drawing 10 denotes the engine base having attached to the bottom thereof the crank casing 11 which may receive lubricant agitated and vaporized by the action of a crank 12 which constitutes a part of the crank shaft 13. The crank 12 is connected by a pitman rod 14 with a pin 15 held in the piston 16. This piston is guided in a cylindrical shell 17 secured to the base 10, and the piston 16 is rigidly connected with a sleeve 18 fitting the outer periphery of the shell 17 so as to be guided thereby for vertical movement. The sleeve 18 has a piston head 19 movable in a cylinder 20 which forms the lower part of the cylinder casting and forms an annular space 21 between its inner surface and the outer surface of the shell 17 for the piston head 19, the latter having suitable packing rings to form a close joint.

The piston 16 first above mentioned is operative in an explosion chamber 22 secured to or forming an integral part with the

lower cylinder 20, and may be water jacketed in any suitable manner. In the present instance the piston is shown at half-stroke of its rising movement so that consequently the gas charge in the explosion cylinder 22 will now be compressed. At the same time a fresh charge of gas is drawn in by the piston 19 from a carbureter indicated herein at 23 and connected by a tube 24 with a conduit 25 connected with the interior of the cylinders 20 and 22 respectively, through ports 26, 27. A check valve 28 will permit the influx of gas from the carbureter into the conduit 25 and comprises a seat member 29 rigidly held in place and interposed between the tube 24 and conduit 25 as shown. A spring 30 serves to hold the valve 28 normally closed.

When the charge in the explosion cylinder 22 is compressed, the gas is exploded by a spark plug 31 driving the piston down until its force is practically expended and the products of combustion will then be exhausted through the exhaust pipe 32 having a port 33 horizontally opposite the gas inlet port 26.

From the above it will be understood that as the piston 19 travels downwardly, the gas charge drawn past the check valve 28 into the conduit 25 during the upward movement of said piston will be compressed in said conduit so that when the piston 16 has moved downwardly far enough to uncover the port 26, the gas will quickly enter the explosion cylinder 22. Inasmuch as only the lower face of the piston 19 is really the active one as far as compressing the gas is concerned, means are provided for relieving any pressure which may be established above said piston in the cylinder 20 during the upward movement thereof, these means consisting of a pipe 34 which connects the annular clearance space 35 with the interior of the engine base 10 and crank case 11. Similarly, the clearance space 36 provided between the double piston shell 16, 18, which is reciprocable relatively to the shell 17, may be vented through a series of apertures 37 in the piston 16, while packing rings 38 will prevent a leakage of gas from the space 21 into the annular space 36. Any excess of pressure in the crank casing may escape through a perforated closure 39.

Changes in the particular construction and organization of some of the elements of my improved engine may be made without

departing from the spirit of the invention.

I claim:

In a gas engine, the combination with a closed casing, a cylindrical shell extending upwardly therefrom, and a charging cylinder surrounding said shell and having an explosion chamber above the end of said shell, of a piston movable in said shell and extending into said explosion chamber, a sleeve movable upon said shell and having an end thereof detachably connected to said piston to coöperate therewith in providing a head in said explosive chamber, a piston head carried by said sleeve within said

charging cylinder, a gas conduit connecting the charging cylinder and a port in said explosive chamber, a gas supply pipe for said conduit, a check valve in the gas supply pipe and opening into said conduit, and a relief pipe connecting said casing and the space between said charging cylinder and said sleeve. 20

In testimony whereof I affix my signature in presence of two witnesses. 25

HENRY F. WILL.
